CLAIM

The ornamental design for a probe for battery charging and discharging, as shown and described.

DESCRIPTION

1. Probe for battery charging and discharging

1.1 : Perspective

1.2 : Front

1.3 : Back

1.4 : Left

1.5 : Right

1.6 : Top

1.7 : Bottom

1.8 : Reference

1.9 : Reference

The reproductions 1.8 and 1.9 are reference views indicating the state of use and are shown for illustration purposes only and form no part of the claimed design.
